(57) CLAIM

The ornamental design for the furniture front, as shown and described.

DESCRIPTION

FIG. 1 is a perspective view of the furniture front in accordance with the present invention;

FIG. 2 is a front view of the furniture front, the back view is not illustrated as it forms no part of the present invention; and,

FIG. 3 is a right side view of the furniture front, the left side view being a mirror image thereof.

The broken lines shown in the drawings are for illustrative purposes only and form no part of the claimed design.
